UNITED STATES PATENT OFFICE.

WILLIS H. SARGENT, OF ST. JOHNSBURY, VERMONT, ASSIGNOR TO THE
E. AND T. FAIRBANKS AND COMPANY, OF ST. JOHNSBURY, VERMONT,
A CORPORATION OF VERMONT.

DESIGN FOR A SCALE-SUPPORTING STAND.

No. 38,024.

Specification for Design.

Patented May 22, 1906.

Application filed January 12, 1906. Serial No. 295,822. Term of patent 14 years.

To all whom it may concern:

Be it known that I, WILLIS H. SARGENT, a citizen of the United States, residing at St. Johnsbury, in the county of Caledonia, State of Vermont, have invented a certain new, original, and ornamental Design for Scale-Supporting Stands.

My invention relates to a new, original, and ornamental design for scale-supporting stands, of which the following is a specification, reference being had to the accompanying drawing, forming part thereof.

In the drawing the figure is a front elevation, slightly in perspective, of a scale-supporting stand embodying my design.

I claim—

The ornamental design for a scale-supporting stand, as shown.

WILLIS H. SARGENT.
